UNITED STATES PATENT OFFICE.

FRANKLIN F. DICKERMAN, OF PHILADELPHIA, PENNSYLVANIA.

DESIGN FOR A CASING FOR STREET-RECEPTACLES.

57,593.

Specification for Design. Patented Apr. 26, 1921.

Application filed July 10, 1920. Serial No. 395,469. Term of patent 7 years.

To all whom it may concern:

Be it known that I, FRANKLIN F. DICKERMAN, a citizen of the United States, residing at Philadelphia, in the county of Philadelphia and State of Pennsylvania, have invented a new, original, and ornamental Design for a Casing for Street-Receptacles, of which the following is a specification, reference being had to the accompanying drawing, forming part thereof.

Figure 1 is a top plan view, and Figs. 2 and 3 are front and side elevations respectively of my casing.

I claim:

The ornamental design for a casing for street receptacles, as shown.

FRANKLIN F. DICKERMAN.
